UNITED STATES PATENT OFFICE.

CLARENCE KITSON AND WILLIAM J. REINHOLTZ, OF MISHAWAKA,
INDIANA.

ABRADING-MACHINE.

No. 844,366.

Specification of Letters Patent.

Patented Feb. 19, 1907.

Application filed December 5, 1905. Serial No. 290,481.

To all whom it may concern:

Be it known that we, CLARENCE KITSON and WILLIAM J. REINHOLTZ, citizens of the United States, residing at Mishawaka, in the county of St. Joseph and State of Indiana, have invented new and useful Improvements in Abrading-Machine, of which the following is a specification.

This invention relates to improvements in machines for cleaning and polishing moldings of various shapes, and more especially such as are fluted or beaded longitudinally on a concave or convex surface—as, for instance, posts, pillars, and legs of dining-tables, buffets, &c.

The object of the present invention is to arrange the die-roller on which the abrading-belt is mounted in such a position as to enable curved moldings to be run either longitudinally under the roller or transversely thereof, so as to polish the same either lengthwise or cross-grain.

With these and other objects in view the invention consists in the construction, combination, and arrangement of parts, all as will be more fully described hereinafter and pointed out in the appended claims.

In the accompanying drawings, Figure 1 is a front elevation of a polishing-machine constructed in accordance with our invention. Fig. 2 is a side elevation of the same. Fig. 3 is a plan view of the bracket for the belt-tightener and the supporting-arm for the die-roller, the same being taken on the line $z-z$ of Fig. 1. Fig. 4 shows end elevations of die-rollers of different shapes. Fig. 5 is a detail in side elevation of a die-roller associated with a curved molding, and Fig. 6 is a similar view showing the die-roller in end elevation and the molding in transverse section.

Like reference characters indicate corresponding parts throughout the several views of the drawings.

In carrying out the invention the mechanism is mounted upon a suitable standard 2, in the upper end of which is journaled a shaft 3, on one end of which is a driving-pulley 4, having a driving power-belt 5 thereon, and on the other end of the shaft is a pulley 6, on which the abrading-belt 7 is mounted.

On the standard intermediate its ends is a grooved guide 8, which may be integral with the standard or secured thereto in any suitable manner. In this guide is mounted an

arm 9, which has a vertically-disposed flange 10, fitted in the groove of the guide and adapted to be adjusted vertically therein by means of a screw-threaded shaft 11, which has a threaded engagement with the arm 9 to support the latter in its guide, the upper end of the shaft being swiveled in the upper end of the guide and provided with a hand-wheel 12, whereby, when the shaft 11 is rotated by said hand-wheel, the arm 9 will be moved up and down in the guide to give the proper tension to the abrading-belt 7, which runs over the die-roller 13, mounted upon an arbor 14, journaled in a bearing 15 in the end of the arm 9. By having the die-roller detachably connected with the arbor 14 rollers of different contour and of different diameter, such as are shown in Fig. 4, may be fitted to the arbor, and it is preferred to have the periphery of these die-rollers covered with a yielding or compressible material, such as felt or rubber, so as to conform to any irregularities or small crevices in the molding operated upon. As shown in the drawings, the arbor may be provided with a roller of convex contour in cross-section, the same being used for polishing grooved or fluted surfaces of molding 16, as shown in Fig. 6; but obviously other shapes may be polished with die-rollers of different configuration—as, for instance, a beaded surface could be polished with die-roller 13^a. (Shown in Fig. 4.)

One of the salient features of the present invention resides in the location or relative arrangement of the die-roller so as to adapt it to operate upon moldings that are curved longitudinally, a fragment of which is shown at 16 in Fig. 5, and for this purpose the arm 9 is preferably curved, so as to extend forwardly and to one side of the standard 2, as shown in Fig. 3, whereby the curved molding may be run longitudinally under the die-roller, as indicated by the arrow in Fig. 2 and transversely or cross-grain, as indicated by the arrow in Fig. 1, and not only is this arrangement especially designed to operate upon the concave face of curved molding, but also upon the convexed face thereof, as will be obvious. When the curved surface of the molding is on a small radius, a correspondingly small die-roller is required, and in order to take up for the slack in the abrading-belt for such rollers and also to use the same roller to polish the curved surface of a larger

arch on the same molding we provide an adjustable belt guide and tightener. This belt-guide is supported from the arm 9 by an upstanding plate 18, which is secured to the 5 arm 9 and which is provided with a thumb-screw 19, the shank of which extends through a slot in the vertical arm of a bracket 20, whose horizontal arm is also slotted longitudinally and fitted with a shank of a thumb-screw 21, which shank also extends through the longitudinally slot in an arm 22, all of which is more clearly shown in Fig. 3. On the free end of this arm 22 is journaled an idler 23, on each end of which is a flange between 10 which the abrading-belt is guided, the idler preferably being disposed above and in the same vertical plane with the guide-roller, as shown, although by the construction above mentioned the idler may be adjusted 15 vertically by releasing the thumb-screw 19 and lifting the bracket 20 and arm 22 and also adjusted horizontally in the same plane with and longitudinally of the axis of the die-roller and also angularly by means of the 20 thumb-screw 21, the shank of which passes through coinciding slots in the bracket and arm 22.

It will be seen that when the idler is adjusted vertically the tension on the abrading-belt may be increased as may be necessary when the die-rollers of small diameters are used, and in such instances the belt will be held away from the front edge of the die-roller and will engage the same at the bottom thereof only, thus giving to the belt a sharp curve at the bottom of the die-roller and a gradual curve from the bottom toward the idler, enabling molding of irregular curvature to be operated upon by a single die- 30 roller of small diameter. Furthermore, the angular and horizontal adjustments of the idler permit the abrading-belt to be brought nearer to one edge of a die-roller when the latter is of such shape as to require the polishing of sharp corners or crevices. Generally, however, the idler may be utilized to 35 tighten the belt when the same is mounted on large die-rollers.

Having thus described our invention, what 40 we claim, and desire to secure by Letters Patent, is—

1. In a polishing-machine, the combination with a standard, a die-roller vertically adjustable therein, said die-roller being journaled in front of and to one side of the standard, whereby 45 an unobstructed space is formed beneath the die-roller, of a combined belt guide and tightener journaled above the die-roller and

adjustable in the same vertical plane therewith and also adjustable in a plane parallel 50 with and longitudinally of the axis of the die-roller, and an abrading-belt mounted on the die-roller, substantially as specified.

2. A polishing-machine embodying a standard, a driven pulley mounted thereon, a 55 guide on the standard, a curved arm vertically adjustable in the guide and extending forwardly and to one side of the standard, a die-roller journaled in end of the arm, and an abrading-belt mounted on the die-roller and 60 the driven pulley, substantially as specified.

3. A polishing-machine embodying a standard, a driven pulley journaled therein, an abrading-belt on said pulley, an arm 75 adjustably mounted on the standard, said arm extending horizontally from the front of the standard and then curved laterally with its free end disposed substantially in the same vertical plane with the driven pulley, to provide an unobstructed space beneath the free 80 end of the arm and a die-roller journaled in the free end of the arm and engaged with the abrading-belt, whereby curved molding may be run longitudinally and transversely under the die-roller when polished.

4. In a machine of the class described, a standard, a shaft journaled in the upper end of the standard, a driven pulley mounted on said shaft, a grooved guide on said standard, an arm having a vertical plate mounted in 90 the grooves of the guide, a threaded adjusting-rod swiveled in the guide and engaged with the arm, said arm being curved and having its free end disposed in front of and to one side of the standard, an arbor journaled in 95 the free end of the arm, a die-roller detachably mounted on said arbor and in the same vertical plane with the driven pulley, an abrading-belt mounted on said pulley and on 100 the die-roller, a bracket vertically adjustable upon said arm and having a longitudinal slot in its horizontal portion thereof, an arm having a longitudinal slot coinciding with the first-mentioned slot and adjustably mounted 105 on the bracket, and a flanged idler journaled on the end of said last-mentioned arm and adapted to engage the abrading-belt adjacent to and above the die-roller, substantially as specified.

In testimony whereof we affix our signatures in presence of two subscribing witnesses.

CLARENCE KITSON.
